(57) **CLAIM**

We claim the ornamental design for a handheld infra-red scanner, as shown and described.

DESCRIPTION

FIG. 1 is an upper left front perspective view of a handheld infra-red scanner showing my new design;

FIG. 2 is a lower left rear perspective view thereof;

FIG. 3 is a right side elevational view thereof;

FIG. 4 is a front plan view thereof;

FIG. 5 is a rear plan view thereof;

FIG. 6 is a top plan view thereof; and,

FIG. 7 is a bottom plan view thereof.

Singular broken lines running along surfaces of otherwise claimed portions of the invention are not claimed. Where there are portions in broken line, the broken lines and portions of space contained within are not claimed.
